UNITED STATES PATENT OFFICE.

PIERRE J. H. BERNARD, OF MONTREAL, QUEBEC, CANADA.

RADIATOR.

Application filed August 22, 1921. Serial No. 494,202.

To all whom it may concern:

Be it known that I, PIERRE J. H. BERNARD, a subject of the King of Great Britain, residing at Montreal, Province of Quebec, Canada, have invented certain new and useful Improvements in Radiators; and I do hereby declare that the following is a full, clear, and exact description of the invention, such as will enable others skilled in the art to which it appertains to make and use the same.

The present invention relates to new and useful improvements in radiators and has for its object the provision of a small hot water radiator which is applicable to the room of a building for the purpose of properly heating the same.

Another object of the invention is the provision of a radiator including one or more casings through which hot water is adapted to circulate, together with means for drawing air therethrough, heating the air and transmitting it into the room of a building or the like in which the radiator is located.

A still further object of the invention is the provision of a radiator such as above referred to which will be comparatively simple and inexpensive to manufacture, reliable and efficient in use, and readily operated.

With the above and other objects in view, the present invention resides in the novel features of construction, formations, combinations and arrangements of parts to be hereinafter more fully described, claimed and illustrated in the accompanying drawings forming a part of the present application, and in which:

40 Figure 1 is a perspective view of the invention, portions being broken away;

Figure 2 is a front elevation of the structure disclosed in Figure 1;

Figure 3 is a transverse sectional view therethrough on the line 3—3 of Fig. 2;

Figure 4 is a horizontal sectional view therethrough on the line 4—4 of Fig. 2.

Referring to the drawings, a heater is provided which may be used in substitution for the usual radiators now employed within the rooms of a building for heating purposes. In this form of the invention, a rectangular casing is shown at 40 and is provided with spaced hollow partitions 41 which extend longitudinally of the casing 40 and form water compartments 42, as will

be hereinafter explained. The top and bottom of the casing 40 are perforated as at 43 and 44 to permit the circulation of air therethrough.

A water supply tank is shown at 45 and is connected with the water compartments 42 at their upper ends through a main pipe 46 provided with branch pipes 47, while the said tank 45 is likewise connected to the lower ends of the water compartments 42 by the lower pipe 48 and branch pipes 49. The pipe 48 is provided with an ordinary form of faucet 50 by means of which water can be drawn from the device. The water heater 70 casing is shown at 51 and contains an electric heating element. It is connected by a pipe 52 and branch pipe 53 to the upper ends of the compartments 42 formed within the partitions 41, while the said casing is likewise connected to the lower ends of these said compartments 42 by a pipe 54 and branch pipes 55. It will thus be seen that the heated water circulates freely from the casing 51 through the several compartments 42 in a continuous flow of hot water which heats the air sucked into the casing through the openings 44 which air is expelled through the openings 43 at the upper end of the drum for heating the room in which the device is applied.

In this form of radiator, the circulation of water heats the air passing into the lower end of the casing upwardly therethrough and out through the upper end for the purposes of conveniently and economically supplying heat to the room of the building in which the said radiator is located.

From the foregoing description, taken in connection with the accompanying drawings, it will be manifest that a radiator is provided which will fulfil all of the necessary requirements of such a device, and it should be understood in this connection, that various minor changes in the specific details of construction can be resorted to within the scope of the appended claims, without departing from the spirit or sacrificing any of the advantages of the invention.

Having thus fully described the invention, what I claim as new and desire to protect by Letters Patent is:

1. The herein described radiator, comprising a rectangular casing, rectangular hollow members in said casing, means for circulating water through the rectangular

hollow members for heating purposes, and means for allowing circulation of air through the casing and between said hollow members to be heated by the water contained therein.

2. The herein described radiator comprising a rectangular casing, said casing having water compartments located therein, said casing having air passages arranged therein, and a tank operatively connected to the water compartments for supplying water thereto.

3. The herein described radiator comprising a rectangular casing, hollow partitions within said casing, means for circulating hot water therethrough, the top and bottom ends of the casing having perforations therein providing air passages between the partitions of the casing, and a water supply tank for supplying water to the hollow partitions of the casing.

In witness whereof I have hereunto set my hand.

PIERRE J. H. BERNARD.
